UNITED STATES PATENT OFFICE

ADOLPH SELIKOWITZ, OF BROOKLYN, NEW YORK, ASSIGNOR TO METROPOLITAN IMPORTING & MFG. CO., OF NEW YORK, N. Y., A CORPORATION OF NEW YORK

DESIGN FOR A COMBINED TELEPHONE INFORMATION CARD AND MAGNIFYING GLASS

Application filed May 18, 1931. Serial No. 39,889. Term of patent 3½ years.

To all whom it may concern:

Be it known that I, ADOLPH SELIKOWITZ, a citizen of the United States, residing at Brooklyn, in the county of Kings, State of New York, have invented a new, original, and ornamental Design for a Combined Telephone Information Card and Magnifying Glass, of which the following is a specification, reference being had to the accompanying drawing, forming part thereof.

Fig. 1 is a face view of a combined telephone information card and magnifying glass, showing my new design; and Fig. 2 is an end view of the same, the double convex element in the center of the card being a magnifying glass.

I claim:

The ornamental design for a combined telephone information card and magnifying glass as shown and described.

In testimony whereof I affix my signature.
ADOLPH SELIKOWITZ.
